ATTORNEY

UNITED STATES PATENT OFFICE.

JOHN N. SQUIER, OF JACKSON, MICHIGAN.

GUN-STOCK.

SPECIFICATION forming part of Letters Patent No. 268,374, dated November 28, 1882.

Application filed July 15, 1882. (No model.)

To all whom it may concern:

Be it known that I, JOHN N. SQUIER, of Jackson, Jackson county, State of Michigan, have invented a new and useful Improvement in 5 Gun-Stocks; and I do hereby declare that the following is a full, clear, and exact description of the same, reference being had to the accompanying sheet of drawings, making part of this specification.

10 This invention is in the nature of an improvement in gun-stocks; and the invention consists in a gun-stock with a flat steel spring fitted to its butt, so that the ends of said spring may have lateral or end play, as is more particularly described hereinafter.

In the accompanying sheet of drawings, Figure 1 is a side elevation, partly in section. Fig. 2 is a plan. Fig. 3 is a cross-section, taken in the line *xx*, Fig. 1. Fig. 4 is a plan of spring 20 removed; Fig. 5, a side elevation of stock and hood, partly in section.

Similar letters of reference indicate like parts in the several figures.

The purpose of this invention is to protect 25 the shoulder of the user of a gun from the shock of the recoil of the gun when fired. It is the common experience of sportsmen and others using guns that a constant use of the gun results in lamming the shoulder of the user, 30 the injury proceeding from the shock communicated by the recoil of the gun. Various devices have been applied to gun-stocks to prevent injury from this cause, most of which are in the nature of cushions of india-rubber, 35 or a combination of spiral springs. By my invention it is believed a simple and efficacious preventive is had without weakening the gun-stock or marring its appearance.

To that end I construct my gun-stock with 40 a flat spring, A, of steel or other suitable material, and of a shape and size corresponding to the cross-section of a stock at its butt. The ordinary metal heel-plate of the stock may then be removed from the gun and the curvature in the end of the stock or butt may be 45 deepened to some extent.

To the butt of the stock, at the ends of the curvature *a*, are secured in any suitable manner metal plates B, with a space, *b*, between 50 them and the stock. The metal spring A, with its ends terminating in tongues or ten-

ons *c*, is secured to the butt of the stock by inserting these tongues or tenons beneath the plates B and into the spaces or openings *b*, by which means the spring is confined to the butt 55 of the stock, so that it cannot be accidentally detached therefrom, and yet its ends can have free lateral play.

Now, when the gun is provided with an elastic spring, substantially as is hereinbefore 60 described, and the gun is raised to the shoulder for the purpose of firing it, the spring A is brought immediately in contact with the shoulder and is interposed between the shoulder and the stock, so that when the gun is 65 fired this spring A will yield its elasticity by bending in the curvature *a*, thereby acting substantially as an elastic cushion, taking the shock of the recoil and preserving the shoulder from injury. As the spring A by the force 70 of the recoil is bent inward the ends of the spring, having free lateral play, are withdrawn to some extent from beneath the plates B, thereby permitting the elastic action of the spring. Immediately after the firing the spring 75 recovers its normal position by its own resiliency. If desired, this spring A may be padded, as shown in Figs. 1 and 3, or it may be plated and finished in any suitable manner, and if padded a leather hood, C, should 80 be provided to inclose the butt of the stock and cover the spring and its pad. This hood may be permanently secured to the stock, or it may be fixed thereto by means of a lacing-string, so as to render it easily removable. 85 The hood, however, will be found useful under all circumstances, particularly when passing through underbrush, to prevent the spring from catching.

Having now described my invention, what I 90 claim as new, and desire to secure by Letters Patent, is—

1. A gun-stock the butt whereof is provided with the usual or a greater or less curvature, combined with a flat metallic spring extending 95 across such curvature and held in place by end plates attached to the stock, substantially as and for the purpose described.

2. The combination, with a gun-stock provided with the butt recess or curve *a*, of a flat 100 spring extending across such recess and having end tongues and held in place by plates

secured over such tongues to the stock, substantially as and for the purpose described.

3. The combination of a gun-stock having a butt recess or curve, the flat spring A, provided with tongues c, and secured to said stock over or across its recess by plates B with the hood e, substantially as and for the purpose described.

4. The combination, in a gun-stock, of a flat

spring, A, secured over a recess or curve in the butt of a stock, and a padded covering for said spring, substantially as and for the purpose described.

JOHN N. SQUIER.
